UNITED STATES PATENT OFFICE.

JAMES BARKER, OF PHILADELPHIA, PENNSYLVANIA.

DESIGN FOR A FOOT-REST FOR DENTIST AND BARBER CHAIRS.

No. 38,774.

Specification for Design.

Patented Aug. 27, 1907.

Application filed April 29, 1907. Serial No. 371,023. Term of patent 14 years.

To all whom it may concern:

Be it known that I, JAMES BARKER, a citizen of the United States, residing in Philadelphia, Pennsylvania, have invented a certain new, original, and ornamental Design for Foot-Rests for Dentist and Barber Chairs, of which the following is a specification, reference being had to the accompanying drawing, forming part thereof, in which:—

Figure 1, is a plan view of the foot rest; and Fig. 2, is a side view.

I claim:—

The ornamental design for a foot rest for dentist and barber chairs as shown.

JAMES BARKER.
